UNITED STATES PATENT OFFICE.

OLIVER M. EDWARDS, OF SYRACUSE, NEW YORK, ASSIGNOR TO THE O. M. EDWARDS COMPANY, INC., OF SYRACUSE, NEW YORK, A CORPORATION OF NEW YORK.

SASH-HOLDING MEANS.

1,251,199.

Specification of Letters Patent. Patented Dec. 25, 1917.

Original application filed December 24, 1909, Serial No. 534,796. Divided and this application filed June 2, 1916. Serial No. 101,253.

To all whom it may concern:

Be it known that I, OLIVER M. EDWARDS, a citizen of the United States, and a resident of Syracuse, in the county of Onondaga and 5 State of New York, have invented a certain new and useful Sash-Holding Means, of which the following is a specification.

This invention relates to sash holding means which is particularly simple in construction and economical in manufacture and highly efficient in use; and the invention 10 consists in the combinations and constructions hereinafter set forth and claimed.

In describing this invention, reference is 15 had to the accompanying drawings in which like characters designate corresponding parts in all the views.

Figure 1 is an elevation, partly broken away, and partly in section, of a window 20 sash embodying my invention, and the contiguous portion of the window frame.

Fig. 2 is an edge view of the lower portion 25 of a double window embodying my invention, the contiguous portion of the window frame being also shown.

Fig. 3 is a sectional view on the plane of line 3—3, Fig. 1, illustrating my invention as embodied in a sheet metal sash.

Fig. 4 is a detail view of the sash holding 30 means.

I have here shown my invention as embodied in a double sash window, the sashes being provided with holding means tending to force the sashes outwardly in opposite directions, as set forth in my pending application for windows, Sr. No. 534,796 of which application this is a division.

1 and 2 designate the window sashes; 3 the window frame in which the sashes move 40 vertically.

The sashes 1, 2 are similar in construction and in so far as this invention is concerned, one of the sashes may be eliminated. These sashes 1 and 2 move at their opposite edges 45 in guideways 4 formed in the window frame 3, and a stop or parting strip 5 is arranged between the sashes at the opposite edges thereof. As the opposite edges or sides of the windows are alike in construction as 50 shown in my pending application referred to, I have illustrated but a portion of one side of the windows.

Each windowsash 1 or 2 is formed with a recess or cavity opening through the

edge and through the front face thereof. 55 The cavity or space does not open through the face of the sash throughout the entire length of the cavity but only at a point remote from the edge of the sash. The window illustrated in Fig. 3 is formed 60 of thin material as sheet metal so that the sash is hollow and has outer and inner thicknesses of material, or walls which confine a space between them in which the sash holding means is located.

The sash holding means include units 65 located at opposite sides of each sash near the lower edge thereof as shown in my pending application. Each unit comprises a bearing 6 located in the recess or cavity at 70 the outer end thereof at the edge of the sash, an element as a base plate 7 mounted on the face of the sash and closing the opening in said face, and having a bearing 8 extending through the opening in said front 75 face of the sash and into the recess or cavity, the bearing 8 being located in alinement with the bearing 6, outer and inner rock shaft sections 9, 10 journaled in the bearings 6 and 8 respectively, the sections having coupling means on their contiguous ends which interlock and unlock by a relative axial movement of the shaft sections, a holding member as a detent 11 mounted on the outer 80 shaft section 9 at the edge of the sash, and operating means located on the face of the sash and connected to the shaft section 10 to rock the same in the opposite direction. As here shown, the bearing 6 is inserted or sunk into 85 the edge of the sash and is formed with a sink or depression 12 in which the detent 11 is located, and the portion of the face of the sash opposed to the stop 5 or other stop with which the detent co-operates, and one side of 90 the sink 12 are removed so that the detent 95 can coact with shoulders as 13 on this stop.

The means coupling the shaft sections 9 and 10 together is here shown as interfitting or lapping parts, 14, 15 on said shaft sections 9 and 10, and a sleeve 16 encircling the 100 lapping part, the sleeve 16 and the portion of the shaft 10 therein forming a non-circular socket which is complementary to the end 14 of the shaft 9.

The operating means comprises a pinch 105 lever 23 having its handle 24 opposed to a handle 25 projecting from this base plate, this lever 23 extending through a hole in

the base plate and into the cavity or recess and having a hub or bearing 26 which is keyed at 27 to the shaft section 10.

Obviously, by moving the pinch lever 23 upwardly toward the stationary handle 25 the shaft sections 9, 10 will be rocked in such a direction as to carry the detent 11 out of engagement with a shoulder 13.

These shaft sections are moved in the opposite direction to press the detent engaged with the shoulders 13 and to press said detent against the stop 5 in order to force the sash away from the stop 5, by a spring 28 encircling one of the shaft sections and anchored at one end to one of the bearings and connected at its other end to said section.

In the construction shown in Figs. 3 and 4, the spring 28 encircles the shaft section 10 and is anchored at one end to the bearing 8 and is connected at its other end to the hub or the bearing 26 of the pinch lever 23.

The window sashes are also provided with frictional holding devices 33 as described in my pending application.

In operation, and in assembling the parts of the sash holding means and the sash, the bearing with one shaft section therein is inserted through the outer end of the recess 30 or cavity, the element or base plate placed in position in the front of the sash with the inner bearing and shaft section inserted through the opening in the face of the sash, and the shaft sections brought into interlocking engagement by axial movement of the outer shaft section inwardly.

Upon axial movement of the outer shaft section outwardly, said shaft section separates from the inner shaft section and is removable without removing the bearing 12 therefor.

What I claim is:

1. In a window, the combination of a frame, a sash movable in the frame and including a portion formed with a transversely extending cavity having front and

rear walls, the cavity opening at one end through one edge of the window sash and opening at its other end through the face of the sash, and sash holding means comprising inner and outer sections, the two sections having means which interlock one with the other by an endwise sliding movement, and by which the inner section supports the outer, a bearing for the outer section at the outer end of the cavity, and at the edge of the sash, a plate on the face of the sash and covering the opening at the inner end of the cavity, the plate carrying on its inner side the inner section, an operating member associated with the latter section, and a holding member mounted on the outer end of the outer section, substantially as and for the purpose described.

2. In a window, the combination of a frame, a sash movable in the frame and having cavities extending transversely thereof, the cavities opening at their outer ends through the opposite side edges of the sash and at their inner ends through the face of the sash, independently operable sash holding devices located in the cavities, one device in each cavity, each device comprising inner and outer sections in each cavity, holding means at the outer end of the outer section, a plate mounted on the face of the sash and extending through the opening at the inner end of each cavity and supporting the inner section, and operating means associated with said plate and connected to the inner section, the sections of each holding device having means interlocking one with the other by an endwise movement and by which the outer section is supported at its inner end by the inner section, substantially as and for the purpose specified.

In testimony whereof, I have hereunto signed my name, at Syracuse, in the county of Onondaga, and State of New York, this 24 day of May, 1916.

OLIVER M. EDWARDS.
